UNITED STATES PATENT OFFICE.

MORRIS BORISOFF, OF CHICAGO, ILLINOIS.

FOLDING CHAIR.

Application filed August 17, 1923. Serial No. 657,878.

To all whom it may concern:

Be it known that I, MORRIS BORISOFF, a citizen of the United States, residing at 1305 North Washtenaw Avenue, Chicago, county of Cook and State of Illinois, have invented a new and useful Improvement in Folding Chairs, of which the following is a specification.

The invention relates to improvements in 10 folding chairs and particularly in chairs for automobiles and similar vehicles. In addition to the upholstered seats provided in these vehicles the latter are frequently equipped with auxiliary chairs which may be folded out of the way when not in use.

It is an object of the invention to provide an auxiliary chair which can readily be folded away and which when taken into use can be adjusted to different heights so 20 as to accommodate children or adults, as required.

It is also an object of the invention to provide a folding auxiliary chair of this character which utilizes as a seat portion 25 a fabric suitably supported on rigid parts of the chair so as to reduce to a minimum the space to which the chair may be folded.

It is furthermore an object of the invention to provide a chair of this character 30 with a yielding support, thereby dispensing with the necessity of providing a yielding or resilient seat portion to absorb the shocks which are transmitted to the body of the vehicle and which would be otherwise transmitted to the seat itself.

Another object of the invention is to provide an auxiliary chair of this character 35 which can readily be retained in adjusted position at the desired height, and in which, independently of the height of the seat above the floor, also may be adjusted to different heights from the floor.

Another object of the invention is to combine with the supporting element or post 40 of a chair of this character an arm, longitudinally of which said support or post is adjustable so as to vary the locations of the chair, when in use, independently of other adjustments.

It is furthermore an object of the invention 45 to provide a common support for several auxiliary chairs of this character and to render the several chairs operable independently of each other, whereby as many

of the chairs as desired may be placed into 55 operative position while the others are left in folded condition.

The invention also contemplates the provision of an auxiliary chair of this character which can be manufactured at relatively low expense from a smaller number of parts than heretofore used and which can readily be locked in operative position so that a collapse of the chair will be prevented. 60

With these and numerous other objects in view, an embodiment of the invention is described in the following specification and the novel features are pointed out in the accompanying claims. In the specification 70 reference is made to the accompanying drawings illustrating an embodiment of the invention, and in the drawings:

Fig. 1 shows in a plurality a top plan view of these auxiliary chairs with portion 75 of an automobile;

Fig. 2 is a vertical sectional view through one of the auxiliary chairs in operative position;

Fig. 3 is partly front elevation and partly 80 sectional view of one of said chairs in operative position;

Fig. 4 shows the chair in folded and sectional view;

Fig. 5 is a horizontal sectional view 85 through the locking mechanism on a larger scale;

Fig. 6 is a detail sectional view of a strap connection, and

Figs. 7 and 8 are top plan and perspective views respectively of the means for securing the chair slidably on a bar. 90

The support of the foldable auxiliary chairs comprises bearing brackets 1 secured to the bottom of the car and in which a tubular shaft 2 is mounted. According to Fig. 1 a single shaft may be utilized for supporting a plurality of chairs. This shaft 2 carries intermediate its ends for each chair an arm 3 provided with a socket 4 to receive the bar 5 preferably of circular cross-section and rigidly secured to the arm by a rivet or pin 6. 95

A sliding head 7 is carried by the bar 6 and may be secured in adjusted position along said bar by the set screw 8, Figs. 2, 4, 7 and 8.

The head 7 also serves as a carrier for a

yielding base or shock absorber by means of which the upright supporting structure forming the leg of the chair is resiliently braced against the bottom of the car. For this purpose opposite sides of the head 7 are shown flattened at 10 in Fig. 8, these flat portions being of a width sufficient to accommodate each a spring 12 having an upright part 11 and a lateral transverse portion 10 which terminates in a lower spring element 13 in engagement with the bottom of the car when the chair is in operative position. The head 7 is provided adjacent the edges of the flat sides 10 with projections 10' to assist in preventing pivotal movement of these spring brackets about a bolt 14 which extends through the brackets and through head 7 is secured in position by the nut 15.

The upper ends of the upright parts 11 of the spring brackets 12 are furthermore connected with the sides of a tubular post 16 in which the vertical support or leg 17 of the chair is slidably mounted. This leg is provided with ratchet teeth or similar elements 18 indicated here as being of the general shape of a buttress thread and the tubular post 16 carries near its upper end in rigid connection therewith a collar 19, having a radial extension 20 in the cavity 30 of which a locking member 21 is slidably mounted. This locking member terminates in a nose or tooth 22 and is under control of a spring 23. Its outer end projecting from the cavity carries a suitable handle 22 whereby the tooth 22 overcoming the action of the spring 21 may be withdrawn from locking engagement. The support 17 may then be adjusted longitudinally relatively of the tubular post 16 or this support may 40 drop under its weight and that of the frame structure combined therewith, sliding downward in the tubular post.

A head 25 at the top of the leg 17 serves as a support for two lateral brackets 26 which are secured to the head by screws or some other suitable fastening means. They extend from the head 25 in opposite directions and are provided with relatively short laterally projecting parts which are extended by angularly offset pieces 27, these offset or crank portions being located approximately midway between the head 25 and the outer ends of these brackets 26. The crank portions 27 are integral with 55 additional lateral extensions the outer end of which again are angularly offset at 28 forming the upper or head ends of these brackets.

The crank portions 27 which are approximately midway between the central post 16 and the outer sides of the chair serve for the pivotal attachment of braces 29 for the foot rest 30, the upper ends of the braces being provided with openings through 65 which extends the transverse bar 31 having

its ends supported in the crank portions 27. From Figs. 2 and 3 it will be noted that these foot rests braces 29 are twisted 90 degrees intermediate their ends, whereby the terminal portions of the braces opposite 70 their pivot ends extend forward as substantially flat bars adapted to serve for supporting the foot rest 30. These foot rest braces combined with the foot rest proper therefore, constitute a structure which is 75 rigid in itself but pivotally mounted on the transverse bar 31.

A seat supporting structure is secured pivotally to an upper transverse bar 32, which connects the head ends 28 of the lateral brackets 26. According to Figs. 2 and 3, this seat supporting structure comprises two bail shaped members 33, 34 one on each side of the chair and each pair pivoted to the same end of the transverse 80 pivot 40. The legs 35 and 36 of these bails are flattened at their inner ends at 37, whereby the folding of the structure is facilitated. The transverse bars 38, 39 of these bail shaped members serve for the attachment of a seat fabric 40, the marginal portions of which are placed about these transverse bars and then secured by stitching or in some other suitable way to the seat fabric proper, as indicated in Fig. 2. 85 This seat structure formed by the bail shaped members 23, 34 and seat fabric 40 is therefore a foldable structure adapted to be brought into a compact shape when desired as indicated in Fig. 4.

The transverse member 38 of the forward bail 34 also serves for the attachment of straps 41 which are secured at their lower ends to the foot rest 30 and which are provided with suitable buckle devices 42 or the like, whereby the effective length of these straps may be carried. These straps 41 preferably made of leather, canvas or the like maintain the foot rest at a predetermined selective distance from the seat fabric, 110 whereby the foot rest 29 may be adjusted in each of these auxiliary chairs in accordance with the length of the legs of the occupant to provide for the most comfortable position.

Reinforcing braces to render the entire structure adapted to enhance the rigidity of the structure without interfering with its foldability into compendious form, extend at 43 from the lower transverse pivot 31 to which the foot rest is braced. The braces 43 extend to the transverse member 39 of the rear bail 33. The braces are formed by bars having their upper outer ends 44 pivotally secured near the outer ends of the transverse member 39 and having their inner lower ends detachably fastened to the lower shorter transverse pivot 31. For this purpose the brace bars 43 are provided with angularly offset portions 45, and their inner and lower 125 130

ends are bifurcated at 46, so as to partly embrace the transverse pivot 31. As disengagement of the bifurcated end 46 from the bar 31 might occur upon violent jolts of the vehicle a safety device in the form of a pivotal hook 47 is loosely and pivotally connected with the front end of the braces 43. This hook 47 will ordinarily by its own weight drop into the operative or locking position shown in Fig. 2 but may readily be removed by the user of the device when it is desired to fold the chair.

The chair, furthermore, comprises a back rest and arm rests, which elements are also secured foldably to the frame structure so as to lend themselves to being placed into the operative position, as shown in Figs. 2 and 3, or into the inoperative position, as illustrated in Fig. 4 in which the entire chair structure is shown folded, and in this condition it will not interfere with the foot space available to the occupants of the main seat of the vehicle.

The back rest includes two uprights 48 preferably constructed as flat bars and rigidly connected at their upper ends by a board 49 which may be provided with suitable upholstery or the like. This back rest formed by the flat bars 48 and connecting element 49 would have a tendency under pressure exerted by the back of the occupant against the connecting board 49 to spring about the transverse bar 39 of the bail shaped member 33 and in order to retain the back rest in operative position a locking device is provided.

The arm rest structure includes flat bars 50 and 51 having at their lower ends eyes or loops 52 by means of which they slidably embrace the legs 36 of the rear bail 33. These bars extend in operative position at about an angle of ninety degrees from these legs 36 and are bent at their upper ends at 53 to afford supports for arm rests 54 which may be made of wood or some other suitable material. While the lower ends of these flat bars 50, 51 are pivotally connected with the legs 36 of the bail 33, the upper ends of the same are rigidly interconnected by a flat bar 55 riveted thereto at 56. The rear projecting end of this connecting bar 55 is hook shaped at 56 and the extremity of the hook is slightly bent inward so as to frictionally engage the sides of the uprights 48 for the back rest Fig. 6. These hooks, therefore, also act as locking means to prevent the movement of the back rest rearward, but when it is desired to fold the entire structure the operator forces the bars 48 of the back rest out of frictional engagement with these hooks 51 to swing the back rest structure about the transverse bars 39 of the bail 33. He then may fold the arm rests about the side bars of the bail 33, and

finally also after loosening the braces 43, 65 may fold the two bails about the pivot 32, as shown in Fig. 4 to reduce the chair to compendious form.

From the above description, it will be seen that a folding chair has been provided which is extremely well adapted to be placed into the tonneau of an automobile and which can readily be folded out of the way when not desired. It is also understood that while several of these chairs may be mounted together on a common support formed by the tubular shaft, each one of these chairs may be operated independently of the others, and that each of these chairs is separately yieldingly supported with respect to the bottom of the tonneau so as to absorb the vibrations and shocks which ordinarily are felt by the occupants of auxiliary chairs more than by the occupants of the chairs provided with the usual upholstery. These auxiliary chairs are furthermore extremely well adapted for individual adjustment of the foot rest so that children or adults may make use of these chairs with great comfort.

This adjustment does not only extend to the proper dimensioning of the height of the seat with respect to the floor but also to the adjustment of the foot rest relatively to the seat—all of which independent effects can be quickly accomplished.

If it is desired to fold the chair away from the operative position, illustrated in Figs. 1 2 and 3 to the position shown in Fig. 4, it is advisable to withdraw the locking tooth 22 so as to permit the post 17 to slide by its own weight into the tubular retainer 16. This, however, is not essential. Upon loosening the set screw 9 the carrier 7 may be moved along the bar 5 until the structure engages the front end of the arm 4 on the common shaft 2.

I claim:

1. A folding chair comprising a sub-structure, an upright pivotally connected with the sub-structure, a collapsible seat structure pivotally secured to the upright, a back rest and arm rests, said back rest and arm rests being pivotally mounted on the seat structure.

2. A folding chair comprising a sub-structure, an upright pivotally mounted on said sub-structure, a pair of seat supports pivotally secured to the upright, a back rest and a pair of arm rests, said back rest and arm rests being pivotally secured to one of said seat supports.

3. A folding chair comprising a sub-structure, an upright pivotally secured to the sub-structure, a pair of bail shaped members each comprising a transverse bar and two leg portions pivoted to said upright, and a back rest pivotally mounted on said transverse bar of one of said bail shaped ele-

ments, and arm rests pivotally secured to the leg portions of the same bail shaped element.

4. A folding chair comprising a sub-
5 structure, an upright pivotally secured to the sub-structure, a collapsible seat support pivoted to the upright, a back rest, a pair of arm rests, said back rest and arm rests being pivoted to said collapsible seat sup-
10 port, and means for releasably interlocking the back rest with the arm rests.

5. A folding chair comprising a sub-
15 structure, a tubular upright secured to the sub-structure, a sliding bar within said tu-
20 bular upright, a collapsible seat support pivoted to said sliding bar, and means com-
25 prising a brace and hook for bracing and detachably connecting said seat support against an extension on said sliding bar.

20 6. A folding chair comprising a sub-
25 structure, an upright pivotally connected with the sub-structure, a bifurcated exten-
30 sion on the top of said upright, a pair of transverse bars extending between the
35 prongs of said extension, a collapsible seat structure pivotally secured to one of said transverse bars, and a brace for said col-
40 lapsible seat structure detachably secured to the other one of said transverse bars.

30 7. A folding chair comprising a sub-
35 structure, an upright pivotally related to the sub-structure and foldable towards the same, a bifurcated extension on the top of
40 said upright, a pair of transverse bars ex-
45 tending between the prongs of the extension, a collapsible seat structure pivotally mounted on one of said bars, a brace inserted be-
50 tween the collapsible seat structure and the other one of said bars, and a foot rest piv-
55 otally connected with one of said transverse bars.

8. A folding chair comprising a sub-
45 structure, an upright pivotally related thereto and foldable towards said sub-
50 structure, a bifurcated extension on the up-
55 right, a pair of transverse bars extending at different levels between the prongs of said extension, a collapsible seat support pivot-
60 ally mounted on the upper one of said trans-
65 verse bars, a brace extending between a por-
70 tion of said seat support and the other one of the transverse bars, and a foot rest piv-
75 otally connected with the second one of said transverse bars.

55 9. A folding chair comprising a sub-
60 structure, an upright pivotally related to said sub-structure and foldable in direction towards the same, a bifurcated extension on said upright, transverse bars extending at
65 different levels between the prongs of said extension, a collapsible seat support non-
70 detachably secured to an upper one of said transverse bars, a brace inserted between a portion of said collapsible seat support and
75 the other one of the transverse bars and de-

tachably connected therewith, and a foot rest also detachably connected with said last named transverse bar and flexibly connected with another portion of said collapsible seat support. 70

10. A folding chair comprising a sub-
75 structure, an upright pivotally related to said sub-structure and foldable in direction towards the same, a bifurcated extension projecting from the top of said upright, 75 transverse bars extending between the prongs of said extension, a collapsible seat support pivotally mounted on the upper one of said transverse bars and comprising two bail shaped elements pivotally secured at 80 the ends of the prongs to said transverse bar, a brace interposed between a transverse part of one of said bail shaped elements and another of the transverse bars between the prongs of the extension, a foot rest detachably connected with said second transverse bar between the prongs of the extension, a back rest, and means for retaining said back rest in operative position, said back rest being foldable towards and away from the 90 collapsible seat support. 85

11. A folding chair comprising a sub-
95 structure, an upright pivotally related to said sub-structure and foldable in direction 100 towards the same, an extension on said up-
right, transverse bars secured to said ex-
105 tension, a collapsible seat support mounted on one of said transverse bars, a brace adapted to retain said collapsible seat sup-
110 port in operative position and detachably connected with the other transverse bar, and a foot rest pivotally connected with the other transverse bar and attached to the seat support. 115

12. A folding chair comprising a sub-
115 structure, an upright pivotally supported by said sub-structure, a bifurcated extension on the sub-structure, a collapsible seat sup-
120 port, a transverse bar in said bifurcated ex-
125 tension and on which the collapsible seat support is pivoted, another transverse bar in said extension, a brace connecting said second transverse bar with the collapsible seat support, a foot rest, and a rigid element detachably connecting said foot rest with 130 said second transverse bar. 135

13. A folding chair comprising a sub-
135 structure which includes a shaft, a rod piv-
140 oted in a plane transversely to the axis of the shaft, an upright pivotally connected with the bar and foldable in direction towards the same, a collapsible seat support pivotally mounted on the upright, and means between said collapsible seat support and the upright for retaining the seat sup-
145 port in operative position. 150

14. A folding chair comprising a sub-
150 structure which consists of a tubular shaft, a bar connected with the shaft and movable in a plane transversely to the axis of said 155

shaft, an upright slidably and pivotally secured to said bar, a collapsible seat support secured to said upright, and a brace interposed between said upright and the collapsible seat support.

15. A folding chair comprising a sub-structure which consists of a tubular shaft, a bar rotatable about said shaft in a plane transversely to the axis of the same, a head

slidably mounted on said bar, springs se- 10
cured to the head, an upright pivotally mounted on the head, a collapsible seat support pivotally secured to said upright, and a brace interposed between said upright and a portion of said collapsible seat support. 15

In testimony whereof, I affix my signature at 7 South Dearborn Street, Chicago.

MORRIS BORISOF.
